UNITED STATES PATENT OFFICE

JOSEPH A. SUMMERLEE, OF DETROIT, MICHIGAN, ASSIGNOR TO BURROUGHS ADDING MACHINE COMPANY, OF DETROIT, MICHIGAN, A CORPORATION OF MICHIGAN

DESIGN FOR A COMBINED CHAIR, SEAT, AND BACK REST

Application filed October 17, 1932. Serial No. 45,377. Term of patent 14 years.

To all whom it may concern:

Be it known that I, JOSEPH A. SUMMERLEE, a citizen of the United States, residing at Detroit, in the county of Wayne and State of Michigan, have invented a new, original, and ornamental Design for a Combined Chair, Seat, and Back Rest, of which the following is a specification, reference being had to the accompanying drawing, forming a part hereof, wherein—

The figure is a perspective view of a combined chair, seat and back rest, showing my new design.

I claim:

The ornamental design for a combined chair, seat, and back rest, as shown.

JOSEPH A. SUMMERLEE,
